UNITED STATES PATENT OFFICE.

ERNST SCHÄEREN, OF BERN, SWITZERLAND, ASSIGNOR TO BUSCH-SULZER BROS.,-
DIESEL ENGINE CO., OF ST. LOUIS, MISSOURI.

HIGH-PRESSURE CRUDE-OIL MOTOR.

Application filed December 15, 1921, Serial No. 522,677, and in Switzerland August 3, 1921.

It is known in high pressure crude oil-motors to effect the starting combustion process of the fuel introduced without the admixture of atomizing air in an auxiliary 5 or antechamber, which is in permanent connection with the working cylinder, in order to force the ignited fuel into the working cylinder by means of the increasing pressure which occurs in the antechamber during 10 ignition, for the purpose of thoroughly mixing the fuel with the oxygen present there. In these known motors the propagation of the combustion process from the antechamber to the working cylinder has been rendered 15 difficult up to the present, in that the fuel ignited in said antechamber was led into the working cylinder only in company with the gases of combustion formed during ignition.

20 The invention relates to a solid injection high pressure crude oil motor, in which the initial combustion of the fuel takes place in an antechamber. The invention consists in surrounding the jet of fuel with a constantly 25 renewed sheath of oxygen. The preferred embodiment of the invention consists in an elongated chamber surrounding the fuel jet and a second chamber extending radially from the elongated chamber which is not 30 telescoped with it and has no uncooled wall separating it from the elongated chamber. Air flows from the radial chamber into the elongated chamber so as to form a constantly 35 renewed sheath of oxygen surrounding the jet of fuel which thus sustains ignition over a large surface.

A mode of execution according to this invention is shown in the drawing.

25 *a* is the working cylinder, *b* the piston, *c* the inlet valve, *d* the cooling chamber and *e* 40 the antechamber of the crude oil-motor connected with the working cylinder by means of channels *f*. Said antechamber according to the invention is of such construction that the central space *e* passed by 45 the jet of fuel, is surrounded at its upper side with an annular space *g* freely communicating with the former, which without being passed by the jet of fuel is only swept by the latter tangentially. In consequence 50 of the arrangement of this annular antechamber space it has become possible, after ignition and during the passage of the fuel into the working cylinder to admit fresh 55 combustion air, and thus to ensure a more perfect combustion in the working cylinder than up to the present.

I claim:

20 In a fuel injection engine the combination 60 of a primary explosion chamber in communication with the cylinder, said chamber comprising a tubular space adjacent the cylinder and a second space extending transversely of the first space and of a depth less than the width of the first space, and a water jacket so enclosing said chamber that the interior walls of both of said spaces are 65 equally subject to the cooling action of the water jacket.

25 In testimony whereof I have affixed my 70 signature.

ERNST SCHÄEREN.
